UNITED STATES PATENT OFFICE.

CHARLES C. WHITE, OF CHICAGO, ILLINOIS.

BUILT-IN CABINET.

Application filed December 12, 1921. Serial No. 521,591.

To all whom it may concern:

Be it known that I, CHARLES C. WHITE, a citizen of the United States, and a resident of Chicago, in the county of Cook and State of Illinois, have invented certain new and useful Improvements in Built-In Cabinets, of which the following is a full, clear, and exact description.

The invention relates to kitchen and other cabinets and more particularly to those of the built-in type used in kitchenette apartments. One object of the invention is to provide an improved kitchen-cabinet which includes a refrigerator unit. Another object of the invention is to provide an improved construction which permits units of the cabinet to be assembled at the factory and to be installed with the minimum amount of labor at the place of installation. Another object is to provide an improved cabinet with a refrigerator unit especially adapted for places where room for the refrigerator is restricted.

The invention consists in the several novel features hereinafter set forth and more particularly defined by claims at the conclusion hereof.

In the drawings: Fig. 1 is a front elevation of a cabinet embodying the invention. Fig. 2 is a longitudinal section. Fig. 3 is a horizontal section on line 3—3 of Fig. 1. Fig. 4 is a perspective of one of the end units. Fig. 5 is a perspective of one of the refrigerator drawers.

The invention is exemplified in a cabinet which is adapted to fit in the end of a kitchen formed by side walls 7 and a back wall 8 of the building. The cabinet is adapted to fill the space across one end of the room and to be permanently installed therein. The cabinet comprises a base portion and a superstructure which are formed of separate factory built units which are put together and secured together at the place of installation.

The lower portion of the cabinet is composed of a refrigerating unit 9 which is disposed adjacent one of the walls 7 and a unit 10 adapted to be placed adjacent the other wall 7. These units are spaced apart to form a compartment 11 for the storage of kitchen utensils, such as pans and kettles. The unit 10 consists of sides 12 corresponding in depth to the cabinet and a shelf 13,

all of which are rigidly secured together and assembled at the factory. This unit forms one end of the lower portion of the cabinet and is self-supporting from the floor, the sides 12 being extended to the floor for that purpose. Drawers 12' for bread and the like are slidably mounted in unit 10. A refrigerator unit 9 comprises an enclosing wall 14, insulation 15, and a lining 16 which are extended to form the top, bottom, sides, front and back of the unit and the side walls are extended to the floor so that the unit will be self-supporting. A partition 17 with openings at the top and bottom divides the space in the refrigerator unit into an ice-chamber 18 and a refrigerating compartment 19, the air being caused to circulate under the partitions upwardly through the compartment 19 and back through the ice-chamber 18. A hinged door 20 is provided at the back of compartment 18 so that ice can be placed into the chamber 18 through a door 21 formed in the back building wall 8. A hinged front door 22 provides access to the ice-chamber from the front of the cabinet. A series of drawers are mounted in the front wall of the refrigerator unit and each comprises an insulated front 24, sides 25, a back 26 and a perforated bottom 27.

By using drawers in the refrigerating compartment, the articles to which access is desired will be withdrawn with the drawer and by providing a series of these drawers, the openings through which cold air may escape when a drawer is open will be of minimum area necessary to provide the desired access, so that the cold air losses will be reduced to a minimum. The perforated bottom permits the cold air to circulate vertically through the drawers in succession. The refrigerator unit is completely assembled at the factory and is placed in position adjacent one of the walls 7 so that the space between the refrigerator unit and unit 10 will form a utensil compartment. Shelves 28 and 29 extend across this compartment and are separate from units 9 and 10 and are supported therefrom. A door 30 is provided to close the front of compartment 11 and is hinged to the inner wall 12 of unit 10. The top of the base portion of the cabinet is formed by a board 31 which extends between the building wall

7 and over units 9 and 10 and compartment 11 so that it will form a top for all of them. Vertical strips 32 are secured to the front of the cabinet after the units have been installed to close the spaces between the outer sides of the units and the building walls. A base board 33 is secured across the front of units 9 and 10 and compartment 11 to close the space below the units 10 and shelf 28. This construction is adapted for ready installation in spaces of different widths, because the units 9 and 10 may be spaced apart any distance desired and the only fitting necessary at the place of installation is to cut the work-board 31 to fit between the built walls and the base-board 33 to fit between strips 32.

This construction exemplifies one in which factory built units are used and in which a 20 minimum amount of labor and fitting are required at the place of installation to provide a built-in cabinet comprising a refrigerator unit and other compartments.

The superstructure of the cabinet comprises a unit composed of vertical side members 35, partitions 36 and 37, shelves 38 and 39, all rigidly secured together at the factory and forming the compartments of the 25 desired size and form usually necessary in a kitchen. The compartments are closed by doors 40. A rack 41 is suspended from shelf 38. Sides 35 of the superstructure unit are spaced from the building walls 7 and, after the unit has been placed in position, strips 35 42 are secured to the front of the cabinet to close the spaces between said sides and said walls and a top 43 is fitted between the building walls 7 to close the upper compartments in the upper unit and when it is secured, the 40 unit becomes substantially a built-in structure. This construction exemplifies an upper unit for a kitchen cabinet which may be assembled at the factory and which may be installed in place with minimum fitting, because it is only necessary for the carpenter 45 to get the top-board 43 to fit between the building walls, to secure it to the factory built upper unit and to secure the sides 42 to the front of said unit.

50 The invention exemplifies a kitchen cabinet which is adapted for installation in kitchenette apartments as a built-in cabinet with very little labor necessary at the place of installation. It is adapted for installation in spaces of different widths, because it is only necessary to provide boards 31 and 43 of the desired length to extend between the building walls and strips 42 of sufficient width to close the spaces between the unit sides 35 and the building walls. It is not necessary to provide a back for the cabinet, because the back wall 8 of the building 55 serves for that purpose.

The invention is not to be understood as 60 restricted to the details set forth, since these

may be modified within the scope of the appended claims, without departing from the spirit and scope of the invention.

Having thus described the invention, what I claim as new and desire to secure by Letters Patent, is:

1. In a built-in cabinet, the combination of a plurality of separately built self-supporting end-units adapted to be placed adjacent corners of a room and secured in spaced relation to form a utensil compartment between them, a separate base-board, a board separate from the units and extending over the top of the units, and vertical strips for closing the spaces between the units and the built-in walls.

2. In a built-in cabinet, the combination of a plurality of separately built self-supporting end units adapted to be placed adjacent corners of a room and secured in spaced relation to form a utensil compartment between them, a separate base-board, a board separate from the units and extending over the top of the units and vertical strips separate from the units for closing the spaces between the units and the building walls.

3. A structure composed of two separate factory-built end sections spaced apart and means combined therewith to enclose the space between the sections and form a complete built-in cabinet.

4. A structure comprising separate factory built end sections spaced apart, and means combined therewith to enclose the space between the sections and form a complete built-in cabinet comprising a continuous member across the top thereof.

5. In a built-in kitchen-cabinet, the combination of a self-supporting, self-contained refrigerating unit adapted to form one end of the cabinet, a self-supporting unit adapted to form the other end of the cabinet and spaced from the refrigerating unit to form a utensil compartment between them and a separate top extending over the units and said compartment.

6. In a built-in kitchen-cabinet, the combination of a self-supporting, self-contained refrigerating unit adapted to form one end of the cabinet, a self-supporting unit adapted to form the other end of the cabinet and spaced from the refrigerating unit to form a utensil compartment between them, a separate top extending over the units and said compartment, separate strips for closing spaces between the outer sides of the end units and the building walls and a base-board across the units and the space between them.

7. A structure composed of separate factory built end units, a continuous top for said units, a factory built unit on said top, and means combined with said units to form a built-in cabinet.

8. The combination of a building having side walls and a back wall, a base comprising factory-built self-supporting units placed adjacent the side walls respectively and spaced from one another to form a compartment between them, a separate top for said base fitted to and extending between the said side walls of the building, the back-wall of the building forming the back of the cabinet, and boards for closing the spaces between the base-units and the side walls and floor of the building.

9. The combination of a building having side walls and a back wall, a base comprising factory-built self-supporting units placed adjacent the side walls respectively and spaced from one another to form a compartment between them, a top for said base fitted to and extending between the said side walls of the building, a factory-built unit mounted on the top of said base top and comprising sides spaced from the building walls and shelves rigidly secured together, a separate top for said upper unit fitted to the

space between the building walls, the back wall of the building forming the back of the cabinet, and boards for closing the spaces between the base units and the side walls of the building.

10. The combination of a building having side walls and a back wall, a base comprising factory-built self-supporting units placed adjacent the side walls respectively and spaced from one another to form a compartment between them, one of said units being a refrigerator, a top for said base fitted to and extending between the said side walls of the building, a factory-built unit mounted on the top of said base top and comprising sides spaced from the building walls and shelves rigidly secured together, a separate top for said upper unit fitted to the space between the building walls, the back wall of the building forming the back of the cabinet, and boards for closing the spaces between the base units and the side walls of the building.

CHARLES C. WHITE.
